UNITED STATES PATENT OFFICE.

NELLIE M. DE LANY, OF CLYDE, NEW YORK.

SHOE-LACE HOLDER.

1,091,297.

Specification of Letters Patent. Patented Mar. 24, 1914.

Application filed April 1, 1913. Serial No. 758,202.

To all whom it may concern:

Be it known that I, NELLIE M. DE LANY, citizen of the United States, residing at Clyde, in the county of Wayne and State of New York, have invented certain new and useful Improvements in Shoe-Lace Holders, of which the following is a specification, reference being had therein to the accompanying drawing.

- 10 This invention relates to a shoe lacing device and has for its object the production of a simple and efficient button means for securing the laces upon the shoe without the necessity of tying the same.
- 15 Another object of this invention is the production of a simple and efficient button which will efficiently hold the shoe lace in such a manner as to prevent the lace from becoming accidentally detached from the
- 20 shoe button.

With these and other objects in view, this invention consists of certain novel constructions, combinations and arrangements of parts, as will be hereinafter fully described and claimed.

In the drawings:—Figure 1 is a perspective view of the shoe showing the series of buttons applied thereto. Fig. 2 is a central transverse section through the base of the button showing the head of the button in elevation. Fig. 3 is a transverse section through the base and head of the button before the same is attached to the shoe. Fig. 4 is a detail perspective of the securing base for the button. Fig. 5 is a detail vertical section of a modified form of the invention wherein the head of the button is of the bent oval shape provided with a clamping ridge upon its lower edge. Fig. 6 is a section through the button illustrated in Fig. 5 and taken at right angles thereto. Fig. 7 is a detail perspective of the head of the button illustrated in Figs. 5 and 6.

By referring to the drawings it will be seen that 1 designates the shoe which is provided with the usual parallel rows of buttons 2 upon which is laced the lacing 3 for holding the upper of the shoe closely around the foot. Lace engaging fasteners 4 are carried near the top of the upper of the shoe and above the upper ends of the rows of buttons 2 so as to firmly hold the shoe lace 3 against being detached from the shoe.

Each of the buttons 2 comprises a base 5 plate 5 which is preferably circular in form having downwardly projecting tapering

prongs 6 which are provided with inwardly bent ends 7. These prongs are forced through the upper of the shoe and then bent back to constitute a clamp substantially as illustrated in Fig. 2, the inwardly bent ends 7 firmly gripping the upper or shoe for firmly holding the base of the button upon the upper. These prongs 6 are bent inwardly so as to prevent the same from being accidentally bent away from the shoe as would be the case if the prongs were bent outwardly and in such a manner would not be protected by the circular body of the base section 5. The base 5 is provided with a plurality of upwardly struck knob portions 9 which are formed adjacent or near the outer edge of the body 5 and are adapted to engage the shoe lace 3 to firmly clamp the lace upon the head portion 10 of the button.

The head portion 10 of the button is preferably concavo-convex as illustrated clearly in Fig. 3 and is provided with a downwardly extending centrally arranged shank portion 11 which is provided with a reduced neck 12 fitting through the aperture 13 formed in the base 5. A washer 14 is placed upon the shank 11 and normally engages the shoulder portion 15 formed upon the shank 11 and constitutes means for limiting the inward movement of the head 10 upon the base 5. This shank portion 11 is preferably formed hollow so as to allow the lower end of the shank to be flattened over to constitute a ring portion 16 whereby the head 10 may be firmly held in engagement with the upper or shoe. It will be seen that by having the upwardly struck portions 9 formed upon the base 5, the upwardly struck portions will force the shoe laces up under the concavo-convex head 10 and thereby assist in holding the lace in engagement with the buttons 2. In this manner the lace will be firmly gripped by the buttons and will not have a tendency to be accidentally detached from the buttons.

In Figs. 5, 6 and 7 I have shown an embodiment of the invention wherein the head portion 17 is provided with a shank 18 of similar construction to that as illustrated in Fig. 3, and this shank 18 is provided with a reduced neck 19 and is also provided with a shoulder 20 against which rests the washer 21. The washer 21 also rests upon the upwardly struck portions 9 of the base 5 and limits the inward movement of the shank 18 upon the base. The shank is secured to

the upper of the shoe in like manner to that as illustrated in Fig. 2. The head 17 is preferably formed concavo-convex in cross section and is provided with a downwardly extending flange 22 upon its periphery which is bent back to constitute a smooth lower edge 23 to constitute an efficient gripping means for the shoe lace. The sides of the flanges 22 are provided with notched portions 24 which notched portions are preferably formed above the struck-up portions 9 of the base 5 to allow the shoe lace to pass up under the head and also to be removed from the button when it is so desired. The upwardly struck portions 9 are also adapted to force the shoe lace upwardly and hold the same under the concavo-convex head to constitute an efficient friction grip for the lace.

Having thus described the invention, what is claimed as new, is:—

1. A shoe button of the class described comprising a base provided with a plurality of prongs adapted to engage a support for holding said base in engagement with said support, said base provided with a plurality of upwardly struck portions, a head provided with a downwardly extending shank, said shank provided with a reduced portion at its lower end, a washer positioned upon said reduced portion, a shoulder formed intermediate the ends of said shank and engaging said washer, said washer engaging the sides of said struck-up portions and limiting the downward movement of said head upon said base, said head comprising a concavo-convex body, and said

struck-up portions adapted to force a shoe lace up under said head for holding the lace in frictional engagement therewith.

2. A shoe button of the class described comprising a base provided with a plurality of prongs adapted to engage a support for holding said base in engagement with said support, said base provided with a plurality of upwardly struck portions, a head provided with a downwardly extending shank, said shank provided with a reduced portion at its lower end, a washer positioned upon said reduced portion, a shoulder formed intermediate the ends of said shank and engaging said washer, said washer engaging the sides of said struck-up portions and limiting the downward movement of said head upon said base, said head comprising a concavo-convex body, said head provided with a flange around its edge, said head being substantially elliptical in shape, said flange portion provided with an upturned edge for producing a smooth shoe lace engaging portion along its lower edge, and said flange provided intermediate its ends upon each side of said head with a notched portion for facilitating the entrance of a shoe lace under said head and also for facilitating the removal of a shoe lace from under said head.

In testimony whereof I hereunto affix my signature in presence of two witnesses.

NELLIE M. DE LANY.
